UNITED STATES PATENT OFFICE.

JOHN S. COLLINS, OF TAD, WEST VIRGINIA.

LOCK NUT.

Application filed January 27, 1923. Serial No. 615,845.

To all whom it may concern:

Be it known that I, JOHN S. COLLINS, a citizen of the United States, residing at Tad, in the county of Kanawha and State of 5 West Virginia, have invented new and useful Improvements in Lock Nuts, of which the following is a specification.

This invention relates to lock nuts and has for its object the provision of a combination consisting of a bolt having oppositely threaded portions upon which are engaged nuts, means being provided for engaging both nuts and preventing relative rotation thereof after they are applied.

15 Another object is the provision of a lock nut of this character in which the locking means consists of a resilient peculiarly formed spring washer which co-operates with both nuts for positively preventing 20 them from movement.

An additional object is the provision of a device of this character which is capable of use in a multiplicity of arts, which will be highly efficient and durable in use, positive 25 in its holding action and a general improvement in the art.

With the above and the other objects and advantages in view the invention consists in the details of construction to be herein- 30 after more fully described and claimed and illustrated in the accompanying drawings, in which:

Figure 1 is a side elevation of the device, Figure 2 is an elevation at right angles to

35 Figure 1,
Figure 3 is an end view,
Figure 4 is a longitudinal section,
Figure 5 is a face view of the large nut,
Figure 6 is a perspective view of the 40 washer and
Figure 7 is a perspective view of the small nut.

Referring more particularly to the drawings the numeral 10 designates a bolt which 45 has one portion 11 formed with right hand threads and which has its end portion 12 reduced and provided with left hand threads. In conjunction with this bolt I provide a relatively large nut 13 which is 50 screwed upon the right hand threaded portion 11 and which has its outer face formed with recesses 14. Screwed upon the reduced left hand threaded end portion 12 is a relatively small nut 15 which has its inner face 55 formed with ribs or teeth 16. The means for locking the nuts together consists of an

elongated spring washer 17 of any desired size and here illustrated as having a length equal to the width of the large nut 13 and having its ends formed with projections 18 60 seating within the recesses 14 in such manner that the central portion of the washer will be spaced away from the outer face of the large nut. The outer surface of this washer is formed with a plurality of notches 65 19 for receiving the projections of ribs 16 on the nut 15.

In applying my device, the bolt 10 is inserted through whatever objects or pieces of material are to be held, and the nut 13 is 70 applied and screwed down tightly on the right hand threaded portion 11 of the bolt. The washer 17 is then slipped over the reduced end of the bolt with its projections 18 fitting within the recesses 14, after which 75 the nut 15 is applied upon the left hand threaded portion and screwed down tightly against the washer 17. Owing to the fact that this washer is resilient, it is apparent that the teeth or ribs 16 will slip into the 80 successive notches 19 in the washer until the washer has been thoroughly compressed, whereupon the outward strain exerted by the washer upon the nut 15 will operate to prevent any possible displacement, that is: 85 relative rotation of the nuts. When the device is applied as above described it will have a most efficient holding action and will naturally recommend itself for use in a multiplicity of arts and for a wide variety 90 of purposes.

While I have shown and described the preferred embodiment of the invention it is of course to be understood that I reserve the right to make such changes in the form, 95 construction and arrangement of parts as will not depart from the spirit of the invention or the scope of the subjoined claims.

Having thus described my invention I 100 claim:

1. In combination, a bolt having oppositely threaded portions, nuts screwed onto said threaded portions, and an arch shaped washer located between the nuts and formed with lugs at its ends, one nut being formed with recesses receiving said lugs, the other nut having its face toward the washer formed with a rib, and the confronting side of the washer being grooved to receive said rib.

2. In combination, a bolt having oppositely threaded portions, a nut screwed

onto one threaded portion and having its outer face formed with recesses, an arch shaped washer disposed upon the bolt and formed with lugs fitting within said recesses, the washer being resilient and having its major portion normally spaced away from the face of the nut, the face of the washer

most remote from the nut being formed with intersecting grooves, and a second nut screwed upon the other threaded portion of the bolt and formed with a rib selectively engageable within one of said grooves. 10

In testimony whereof I affix my signature.
JOHN S. COLLINS.
